EARTH MOVING DEVICE

Ellsworth W. Austin, Cedar Rapids, Iowa, assignor to La Plant-Cheote Manufacturing Company, Incorporated, Cedar Rapids, Iowa, a corporation of Delaware

Application March 15, 1935, Serial No. 11,267

5 Claims. (Cl. 254—93)

This invention relates to earth moving devices and has particular relation to hydraulic jacks and jack supporting structures and the method of producing such, which have been found particularly desirable for use with earth moving devices.

In the construction of earth moving devices of the character described in my copending application, Serial Number 742,368 filed September 10 5, 1933, of which the present application is a continuation in part, it is desirable that a hydraulic jack be provided which will be very low in manufacturing cost and which will be extremely simple and reliable in operation. Furthermore, it is desirable that the hydraulic jack act also as a spacing means for spacing certain members apart and also to provide a jack in which means are provided to permit the cylinder to swivel about on a transverse axis as desired.

20 I have provided such a jack and the entire jack may be built up from standard tube, plate and rod forms. A hydraulic jack, constructed according to my invention, may be assembled by welding or bolting the parts together.

25 A general object of my invention is to provide a simple, strong and reliable hydraulic jack structure.

30 A more specific object of my invention is to provide a hydraulic jack structure which may be constructed of standard plates, pipes and rods.

Another object of my invention is to provide a 35 hydraulic jack structure which lends itself readily to assembly by welding or bolting the parts together.

An important object of my invention is to provide a hydraulic jack cylinder not requiring the usual cylinder head flange for bolting on a jack head.

40 A further object of my invention is to provide a hydraulic jack cylinder suitable for employing a metallic cylinder head gasket for sealing under high unit pressure.

Another object of my invention is to provide a 45 simple means for preventing abnormal distortion of cylinder walls during the welding process.

Another object of my invention is to provide a combination of hydraulic jack and spacing means.

Another object of my invention is to provide 50 a simple and strong pivot means in order that the hydraulic jack may pivot about on a transverse axis.

Other and further features and objects of the invention will be more apparent to those skilled 55 in the art upon a consideration of the accom-

panying drawing and following specification, wherein is disclosed a single exemplary embodiment of the invention, with the understanding, however, that such changes may be made therein as fall within the scope of the appended claims, without departing from the spirit of the invention.

In said drawing:

Figure 1 is a side elevational view, partly in elevation and partly in section, of a jack constructed according to one embodiment of my invention. 10

Figure 2 is a fragmentary perspective view of the head end of a cylinder of the jack shown in Figure 1. 15

Figure 3 is a view in perspective of the cradle or spacer means in which the hydraulic jack is supported.

Figure 4 is a view in perspective of the head of the hydraulic jack with a fragmentary portion of the piston rod shown in place. 20

Figure 5 is an elevational view of the head alone taken generally along the line 5—5 of Figure 1; and

Figure 6 is a partial view illustrating a method 25 employed for holding the cylinder in shape while bolts are being welded to the cylinder.

Referring to the drawing, a jack constructed according to one embodiment of my invention is comprised of a cylinder 10, a cylinder end or closure 11, a cylinder head 12, a cradle 13, a piston 14, and piston rod 16. 30

The cylinder 10 may be of any desired material but in order to provide a structure which may be manufactured at a minimum of expense, I preferably utilize standard welded steel tube. The inside wall of the tube may be ground to provide a perfectly cylindrical smooth surface so that the piston 14 may form a fluid-tight seal within the jack. The operative end 10a of the cylinder 10 is ground off to present a true transverse circular end on the cylinder to form a perfect fit with the cylinder head 12. The opposite end 10b of the cylinder 10 is closed by means 35

of a disc-like member 11 which is welded in place in the end of the cylinder, a lip 11a being formed to insure a perfect circular wall of the cylinder during and after welding. The end closure 11 is drilled and tapped in order that a pipe fitting 17 40 may be threaded into the end closure to permit fluid to be forced into and withdrawn from the interior of the cylinder. The piston 14 may be of any desired construction, but the preferred structure here shown is comprised of a two part piston grooved to receive a split ring 14a and a 45

50 piston 14b.

55

leather cup washer 14b. This construction has been found in practice to afford the best seal with the cylinder wall. The piston rod 16 is threaded into the piston and passes through a 5 suitable central opening in the cylinder head 12 and through a packing gland 18 in the cylinder head. Any suitable connecting means, such as the yoke 19, may be engaged to the projecting end of the piston rod.

10 The cylinder head, better illustrated in Figures 4 and 5, is a substantially rectangular plate, both of whose dimensions are substantially greater than the outside diameter of the cylinder 10, in order that the cylinder head may be secured to 15 the cradle 13 as hereinafter more particularly described. The front wall is provided with the boss 18a and packing gland 18, beforementioned, for providing a seal between the piston rod 16 and the cylinder head 12. The rear face of the 20 cylinder head 12 is provided with a circular groove 22 which is concentric with the opening 21 in the center of the head and this groove is of such dimension and diameter as to receive the end 10a of the cylinder 10. The cylinder head thus 25 projects with the cylinder in what may be termed a lip. A packing ring 38 of soft copper or the like is disposed within the groove.

The cylinder is provided with a plurality of bolts 23 which are equally spaced about the 30 outside of the cylinder with the threaded ends 23a projecting beyond the end of the cylinder sufficiently so that they may be passed through openings 24 in the cylinder head to thus afford means for bolting the cylinder head in place on the end 35 of the cylinder. The bolts 23 are preferably secured to the outside wall of the cylinder 10 by welding them thereto, as this construction provides a very inexpensive method of manufacture and permits the use of standard tube for the cylinder 40 10. To facilitate the welding and maintain the cylinder in true circular form, an unusual method of manufacture is employed; namely a metallic plug 100 is tightly inserted within the lip of the cylinder during the welding operation 45 and allowed to remain therein until this member is sufficiently cool to prevent distortion. This method prevents the cylinder from being warped out of round during the welding and thus avoids difficulties which would later arise when the 50 cylinder was being machined and when it was in service.

The cradle 13 is preferably a box-like structure open on both sides and is preferably comprised of top and bottom plates 13a and 13b, respectively, 55 and end plates 13c and 13d. These plates are rectangular sections cut from standard steel plates. The end members 13c and 13d are slightly longer than the outside dimension between the plates 13a and 13b and the plates 13c and 13d 60 project slightly beyond the outside faces of plates 13a and 13b in order to afford projecting lips so that fillets 26 may be built up by depositing metal in the corners at the junctions of the plates. The plates are also welded to each other at the inner 65 corners formed by the junctions of the plates, as indicated at 21.

The plates 13c and 13d are drilled centrally thereof, as indicated at 28, and stub-shafts 29 are placed in these openings and welded in place 70 as indicated at 31 and 32. The plates 13a and 13b may be of a length such as to provide any desired spacing between the stub-shafts 29 and may project beyond the edge of the cylinder head 12. In this way the cradle 13 may be employed as a

spacer for spacing apart the plates or other members in which stub-shafts 29 are held.

Bolts 33 are welded on the inner faces of the plates 13a and 13b with their threaded ends projecting beyond the edge of the cradle to a sufficient extent that they pass through the widely spaced openings 34 in the cylinder head in order that the cylinder head 12 may be bolted to the cradle 13. The cylinder head 12 may not entirely cover the open side of the cradle 13 but this, of course, does not make any difference. The cylinder head 12 may be drilled, as indicated at 36, and a pipe connection 37 welded within the opening 36 to afford means for introducing fluid to and discharging fluid from inside of the cylinder 10.

It is apparent that my invention provides an extremely simple, strong and reliable hydraulic jack structure and mounting therefor which may be built up from standard tube, bolts, plates, 20 rods and fittings at a minimum of expense. It is apparent that modifications may be made by those skilled in the art and such modifications may be made without departing from the spirit and scope of my invention as set forth in the appended 25 claims.

I claim as my invention:

1. In a hydraulic jack, a cylinder head bolted to the cylinder, a box-like cradle adapted to surround the cylinder and open at both sides thereof, 30 bolts secured to the inner faces of the cradle by welding them thereto, and means on the end of the cylinder head for securing the cylinder head to the cradle.

2. In a hydraulic jack, a cylinder formed of 35 standard welded tubing, a disc like member welded to the cylinder, adapted to close off one end thereof and having an opening therethrough, a plurality of bolts welded to the cylinder about the opposite end, and a cylinder head adapted to be 40 received upon the bolts and in close cooperative engagement with the cylinder, the said cylinder head having an opening therethrough for receiving a fitting for bringing fluid into the cylinder.

3. In a hydraulic jack, a cylinder formed of 45 welded tubing, a disc-like member welded to the cylinder and adapted to close off one end thereof, a plurality of bolts welded to the cylinder about the opposite end, a cylinder head of substantially greater diameter than the cylinder, the cylinder 50 head being adapted to be received on the bolts on the cylinder, a box-like cradle having a plurality of bolts welded to the inner faces thereof and the cylinder head being adapted to be received on said bolts to secure the jack assembly within the 55 cradle.

4. In a hydraulic jack structure, a cylinder, a cradle member adapted to surround the cylinder, the cradle and cylinder having bolts extending parallel to the axis of the cylinder and a cylinder 60 head adapted to be bolted over the end of the cylinder and the side of the cradle.

5. In a hydraulic jack structure, a cylinder, a cradle member surrounding the cylinder and spaced therefrom, and securing means on the 65 outer wall of the cylinder and the inner side of the cradle member, the securing means projecting beyond the respective edges of the cylinder and cradle member and the cylinder head adapted to be secured on the end of the cylinder and the 70 side of the cradle to form a closure for the cylinder.

ELLSWORTH W. AUSTIN.
